(57) CLAIM

The ornamental design for a breath activated vaporization adapter for a water pipe, as shown and described.

DESCRIPTION

A portion of the disclosure of this patent document contains material which is subject to copyright protection. This patent document may show and/or describe matter which is or may become trade dress of Evan Pierce. The copyright and trade dress owner has no objection to the facsimile reproduction by anyone of the patent disclosure as it appears in the Patent and Trademark Office patent files or records, but otherwise reserves all copyright and trade dress rights whatsoever. FIG. 1 is a top perspective view of a breath activated vaporization adapter for a water pipe in accordance with the present invention;

FIG. 2 is a right view thereof;

FIG. 3 is a left view thereof;

FIG. 4 is a top view thereof; and,

FIG. 5 is a bottom view thereof.

The broken lines depicting the lettering and branding and the smoke inlet in the drawings are for illustrative purposes only and form no part of the claimed design.
